UNITED STATES PATENT OFFICE.

OSSIP JOSEPH WALINSKY, OF SEA GATE, NEW YORK, ASSIGNOR TO WHITE LUGGAGE CO. INC., OF NEW YORK, N. Y., A CORPORATION OF NEW YORK.

LUGGAGE.

Application filed June 1, 1926. Serial No. 112,793.

This invention relates to luggage and has for an object a suit case equipped with a tray, one end of which constitutes a portion of the wall of the suit case and having the lid divided into compartments, one of which is provided with an independently hinged cover.

According to this invention the front wall of the body of the suit case is of less width than the side walls and the inner faces of the side walls are arranged to provide ledges lying in the same plane as the upper surface of the front wall. A tray is supported by the ledges and is provided with an enlarged head or end portion which when the tray is in position completes the front wall of the case. The lid is sub-divided into compartments by partitions and one of said partitions is provided with a hinged cover which may be lifted independently of the suit case lid. A mirror is preferably provided in this cover.

Other objects, novel features and advantages of this invention will be apparent from the following specification and accompanying drawings, wherein

Figure 1 is a perspective view of a suit case embodying the invention with the cover raised.

Figure 2 is a perspective view of a suit case with the cover closed; and

Figure 3 is a perspective view with the mirror carrying cover raised.

10 represents the body of a suit case to which is hinged the lid 11. The front wall of the body 10 is of less width than the side walls thereof and ledges 13 extend along the side walls of the body with their upper surfaces in alinement with the upper edge 35 of the wall 12. A tray 14 rests upon the ledges 13 and has an enlarged end portion or head 15 which when the tray is in place completes the front wall 12 of the case. Ridges 16 extend from the upper edges of 40 the side walls of the body 10 to engage the inner faces of the side walls of the cover 11.

A pair of partitions 17 divide the lid 11 into three compartments. The cover 11^a of the middle compartment is hinged so that it may swing up into the position shown in Fig. 3 when the lid 11 is closed and on it is mounted a mirror 18. The front walls

of the two end compartments are provided with latches 19 to cooperate with locks 20 on the front wall of the body 10. The central portion of the head 15 is of greater width than the remaining portion and the front wall of the middle compartment is of less width than the remaining portion and rests upon the larger portion of the member 15. Inter-engaging means are provided on the head 15 and the cover for locking the latter to the former.

The tray 14 may be withdrawn from the suit case without raising the lid or it may be lifted out with the lid raised. With the tray in position and the lid raised, the suit case constitutes a portable dressing table. The end compartments in the lid 11 may be provided with suitable fittings for supporting toilet articles or the like. If desired, the tray may be equipped as a writing tablet.

It is of course understood that various modifications may be made in the structural details without in any way departing from the spirit of the invention as set forth in the appended claims.

Having thus described my invention, what I claim as new and desire to secure by Letters Patent of the United States is:

1. A suit case comprising a body having a front wall of less height than the side walls, a lid hinged to said body, ledges on said side walls in alinement with the upper edge of said front wall and a tray supported by said ledges, said tray having an enlarged end portion interposed between the edges of the front walls of the body and of the lid to complete the front wall of said body.

2. A suit case comprising a body, a lid hinged thereto, the front wall of said body being of less height than the side walls thereof and a portion of the front wall of said lid being of less height than the remainder, a tray supported by said body and having an enlarged portion interposed between the edges of the front walls of the body and of the lid to fill the space between the edges of the said front walls of said body and lid.

3. A suit case comprising a body having its front wall of less height than the side

walls, ledges projecting from the inner faces of said side walls, a tray supported by said ledges, a lid hinged to said body, a pair of partitions dividing said lid into three compartments, a separately hinged cover for the middle compartment, said tray having an enlarged head interposed between the edges of the front walls of said body and lid to fill the space therebetween and means for locking said cover to said head. In testimony whereof, I have signed my name to this specification.

10

OSSIP JOSEPH WALINSKY.
